DESIGN FOR A TEMPLATE

Elwood J. Muldoon, Detroit, Mich.

Application May 11, 1945, Serial No. 119,498

Term of patent 7 years

(Cl. D52—1)

To all whom it may concern:

Be it known that I, Elwood J. Muldoon, a citizen of the United States, residing at Detroit, in the county of Wayne and State of Michigan, have invented a new, original, and ornamental Design for a Template, of which the following is a specification, reference being had to the accompanying drawing, forming part thereof.

In the drawing:

I claim:

The ornamental design for a template, as shown.

ELWOOD J. MULDOON.
